United States Patent Office

Des. 222,516
Patented Oct. 26, 1971

222,516

STERILIZATION INDICATOR

Arthur W. Kelson, New York, N.Y., assignor to Propper
Manufacturing Co., Inc., Long Island City, N.Y.

Filed Aug. 31, 1970, Ser. No. 24,768

Term of patent 14 years

Int. Cl. D24—99

U.S. Cl. D83—1

FIG. 1

FIG. 2

FIG. 3

FIG. 1 is a front view of the sterilization indicator;
FIG. 2 is a side view thereof; and
FIG. 3 is a cross-section taken on line 3—3 of FIG. 1,
the undisclosed rear side is flat and plane.

I claim:

The ornamental design for a sterilization indicator, as
shown and described.
